UNITED STATES PATENT OFFICE.

ROBERT JESSE ROSS, OF CROSBY, NEAR LIVERPOOL, ENGLAND.

CANDLE-HOLDER OR SAVE-ALL.

1,355,696.

Specification of Letters Patent.

Patented Oct. 12, 1920.

Application filed June 10, 1919. Serial No. 303,149.

To all whom it may concern:

Be it known that I, ROBERT JESSE Ross, a subject of the King of Great Britain, residing at Crosby, near Liverpool, in the 5 county of Lancaster, in the Kingdom of England, have invented certain new and useful Improvements in Candle-Holders or Save-Alls, of which the following is a specification.

10 The invention has for its object to provide an improved candle holder or save-all for holding candles in candle sticks, which will enable the candle socket to grip candles of various diameters, and also enable candles 15 to be burnt to or very nearly to the very end, thus avoiding waste.

According to this invention, the improved candle holder or save-all is made from a simple blank of sheet tin or other suitable 20 flexible metal or material. That is to say I stamp out from sheet tin or other sheet material, a blank which when bent into shape will produce (a) a ring, (b) a base, and (c) three or any suitable number of tongue 25 pieces. The tongues are adapted to grip the rim or flange of the candle stick socket while the function of one of them is also to press against or grip the inside of the socket. The ring will grip the candle, and the base 30 will form a false bottom or support for the bottom of the candle to rest on, and prevent it descending to the bottom of the candle stick socket or cup. Supplemental means may also be provided for locking the candle 35 in the holder.

The invention will be understood from the following description reference being had to the accompanying drawings, in which:—

40 Figure 1 is the blank from which the candle holder or save-all is made.

Fig. 2 is a view of the candle holder or save-all bent into shape, and

Fig. 3 is a view of a candle stick with my candle holder or save-all applied thereto.

45 The blank when stamped out consists of a disk portion A with a tongue B projecting from one edge, while at the opposite edge is a strip C at about right angles to the said tongue, and of such length as to extend 50 around the outside of the candle. This piece C has one, two or more tongues D projecting laterally from it, and also at the same edge that those tongues project from, two or three or more teeth or prongs E all 55 these parts being integral. This blank is formed up into a socket by bending the disk

portion A at right angles to the strip part C, so as to form the bottom of the holder, then bending the said strip part C into the form of a ring which will expand or contract thus gripping the candle when the lower end of the latter is thrust into it, also the prongs E are bent laterally inward. The tongues B, D are now so bent outward that the holder will rest on the top of the 60 candle stick socket F, and their ends are bent under the rim of the socket thus holding the device in position, or if desired these tongues can be wound into convolutions, so as to rest on top of the candle stick, or bent 65 in any suitable way according to the type of candle stick to which the holder or save-all is to be applied. The tongue B that projects from the edge of the disk portion A of the blank, is first bent upward to the top 70 of the holder before being bent outward, so as to correspond with the other tongues D, such upward bend gripping or pressing against the inside of the candle stick socket F so as to keep the holder in position. The 75 act of pressing the candle into the holder will cause the prongs E to make longitudinal score marks therein, and then by giving the candle the segment of a turn, the prongs will cut into the candle circumferentially 80 thus serving to lock the candle in the holder, and prevent it accidentally coming out. The prongs E in fact form an interlocking 85 connection between the candle and the holder, supplemental to the grip of the strip 90 part of the holder. Instead of prongs, indentations may be punched from the outside of the ring C, so as to form projections on the inside.

The device forms a ventilated candle 95 holder or save-all to which air has free access, so that the candle will burn to or very nearly to the very end. It can be manufactured very cheaply and sold at a small price.

100 I declare that what I claim is:—

1. A candle holder blank comprising a disk portion having a tongue projecting therefrom; a strip connected at one edge with said disk; and a tongue projecting 105 from the opposite edge of said strip.

2. A candle holder blank, comprising a disk portion having a tongue projecting from one edge thereof; a strip connected to the opposite edge of said disk and extending at substantially right angles to said tongue; and a plurality of tongues project-

ing at right angles from the outer edge of said strip.

3. A candle holder blank, comprising a disk portion having a tongue projecting from one edge thereof; a strip connected to the opposite edge of said disk and extending at substantially right angles to said tongue; a plurality of tongues projecting at right angles from the outer edge of said strip; and candle engaging prongs also projecting from the outer edge of said strip.

4. A candle holder or save-all comprising a base, a strip made integral at mid length with this base and bent into the form of a ring, a tongue piece projecting upward from the base so as to lie between the ends of the ring, tongue pieces projecting outwardly from the upper edge of the ring, and prongs projecting inwardly from the said upper edge.

5. A candle holder or save-all comprising a base, a strip made integral at mid length

with this base and bent into the form of a ring, a tongue piece projecting upward from the base so as to lie between the ends of the ring, tongue pieces projecting outwardly from the upper edge of the ring, and indents punched from the outside so as to form projections on the inside of the said ring.

6. A one-piece candle holder comprising a base; a wall extending upwardly from and partially around the periphery of said base; a tongue projecting upwardly from the base between the ends of said wall; and tongues projecting from the upper edge of said wall.

In witness whereof, I have hereunto signed my name this 19th day of May, 1919, in the presence of two subscribing witnesses.

ROBERT JESSE ROSS.
